Attorney.*

UNITED STATES PATENT OFFICE.

PAUL RICHERT, OF PITTSBURGH, PENNSYLVANIA.

LOCKING-SHUTTER FOR TAXIMETERS.

1,033,056

Specification of Letters Patent. Patented July 16, 1912.

Application filed December 5, 1910. Serial No. 595,764.

To all whom it may concern:

Be it known that I, PAUL RICHERT, a resident of Pittsburgh, in the county of Allegheny and State of Pennsylvania, have invented a new and useful Improvement in Locking-Shutters for Taximeters, of which the following is a specification.

This invention relates to taximeters or fare registers for hired vehicles.

- 10 The object is to provide a special shutter or device which conceals from the driver the true condition of the meter, but which enables the owner to readily take the readings therefrom.
- 15 One of the difficulties in operating vehicles for public use is to prevent the drivers from cheating the owners. The present taximeters aim to prevent this as far as possible. It is found however that at times the 20 mechanism of the meter fails to operate or slips, and does not register the amount of the fare collected or the number of miles traveled by the vehicle, or other important matters; discovery of which on the part of 25 the driver induces him in handing in his report card not to report more money received than the meter shows, but to pocket the fares collected over and above what is shown on the meter.
- 30 The present invention has for its purpose to prevent this as far as possible. This is effected by providing special means which conceal from the driver the total amount of the registration, thereby leaving him in ignorance thereof, so that on his report card he will report the total amount collected on the various trips, in the belief that the register will show this amount; but which special means are so arranged that the owner 35 can readily inspect the register and take the readings thereof.

The invention comprises the construction and arrangement of a specially key controlled shutter as hereinafter described and 40 claimed.

In the accompanying drawing Figure 1 is an inside view of the back casing-plate of a taximeter showing my invention applied thereto; Fig. 2 is a vertical sectional view 45 on an enlarged scale taken on the line 2—2, Fig. 1; Fig. 3 is a similar view taken on the line 3—3, Fig. 1; and Fig. 4 is an outside view of a portion of the back plate.

The improvements herein claimed are 50 shown applied to a taximeter of the type

shown and claimed in my application filed September 7th, 1909, Serial No. 516,505, and in the drawings herein only such parts of the meter as are affected by the special improvements are shown. The present improvements however can be applied to taximeters of various types.

In the drawings, 2 represents the back plate of the usual casing inclosing the meter mechanism. The signal or flag is indicated 60 at 3, the same being provided with a lever or shaft 4 which is connected to the flag spindle 5 mounted in the back plate 2 and operating in the usual way of such flags or signals, to indicate either that the vehicle is for hire 65 or is occupied, and serving when moved up and down to operate the indicating and registering mechanism. The indicating mechanism may be of various kinds and is not disclosed herein. The drawing shows 70 the locking lever 6 for the flag, which lever is controlled by a cam member 7 from a knob on the outside, all as in my application aforesaid, for preventing operation of the flag, which knob can be operated from the 75 exterior by the driver.

The drawings show only the totalizing registers of the meter, which are operated from the movements of the flag as is customary. These are shown as corresponding 80 to those of my application above identified and comprise five different sets of registering wheels, marked 10, 11, 12, 13 and 14 respectively and serving respectively to register the totals of the following items, 85 total miles traveled by the vehicle, total miles traveled by the vehicle for which pay is received, the number of trips, the amount of the regular or usual tariff or fare, and the amount of the extra tariff or fares. All 90 of these registers are shown in the form of wheels, which are shown mounted in alignment and preferably upon a common shaft as in my application aforesaid, and which shaft is secured in a frame or housing member 15 secured to the back plate 2. In the 95 back plate in line with these registers is a window 16 through which these registers can be read, said window preferably being closed by a glass held in frame 17 as is the usual practice with taximeters. This window is visible to the driver of the vehicle and ordinarily the readings of these totalizing 100 registers are plainly visible. The present invention provides means for prevent-

105

ing the view of these registers through the window by the driver, as follows: Slidably mounted between the registers and the window 16 is a shutter 20 provided with a series of openings 21, one for each of the registers named. This shutter is shown as formed of sheet metal and has end flanges 22 provided with slots 23 which are engaged by pins 24 projecting from the ends of housing 15. Pivottally connected at 25 to the shutter is one arm 26 of an angle lever pivotally mounted at 27 and whose opposite arm 28 is adapted to be operated by a cam member 29 on the barrel 30 of a suitable key controlled lock, such for instance as a Yale or other like lock having a rotating barrel. A spring 31 connected to arm 26 of the angle lever serves to normally hold the shutter in lowered position, in which position it conceals the registering wheels from the driver. The cam 29 and lever arm 28 are so arranged that the angle lever is actuated by the rotation of the barrel of the lock in either direction. Any suitable lock may be employed but I prefer a lock of the Yale type on account of the difficulty in getting a spurious key to operate the same. The lock is shown clamped by a nut to the back plate, the barrel at the inner end being exposed and having secured to it the cam 29. The key is shown at 33, and when inserted in the lock permits of the rotation of the barrel in the usual way of locks of this kind. Normally the shutter is in lowered position as described, entirely concealing the registering wheels. To expose the registering wheels it is necessary to insert the key in the lock and by rotating the barrel the cam 29 actuates the angle lever 28 which lifts the shutter and brings the openings 21 into line with registering wheels, when the condition of the register can be easily read through the window. It is intended that a key for the lock shall be in the possession of only the owner or his accredited representative. It will be noticed that by the arrangement of cam 29 and lever arm 28, when the cam is rotated to horizontal position, as in Fig. 3, its engagement with the lever will hold the lever in the position shown at dotted lines, the shutter at this time occupying its uppermost position and exposing the totalizer to view. The parts will occupy this position so long as the cam is left in horizontal position. To prevent moisture from entering the lock and through the latter getting into the casing, I provide a cover 35 on the outside. This cover is pivoted on a plate 36 which is clamped between the back plate 2 and the enlarged outer end 37 of the lock. A spring 38 encircles the pivot pin 39 and serves to normally hold the cover to conceal the lock. Said cover is provided with a curved projection 40 which can be easily grasped to lift the cover.

As a result of this invention, the driver does not know the true condition of the totalizing registers, does not know whether there has been any failure on the part of the latter, but will naturally suppose that the register has operated perfectly, and consequently will keep his report correctly according to each trip run. Consequently his report card at night will show the true amount of fares received by him, and the owner receives the money due him entirely irrespective of whether there has been a failure in the totalizing register or not.

Any suitable form of lock is adapted for the purpose, and the connection between the key controlled portion of the lock and the shutter may also be variously arranged without departing from the spirit of the invention.

What I claim is:

1. In a taximeter, the combination of a casing provided with a window, a totalizing register located to be viewed through said window, a shutter slidably mounted on the inner wall of the casing and arranged to cover the window in its normal position, a key controlled barrel lock extending through the casing, and operating connections between the lock barrel and shutter, said connections being mounted on the casing and arranged when the lock barrel is rotated to move the shutter to expose the register through the window.

2. In a taximeter, the combination of a casing provided with a window, a totalizing register located to be viewed through said window, a shutter mounted to slide in ways upon the casing and arranged to cover the window in its normal position, a key controlled barrel lock extending through the casing, a cam on the barrel, an angle lever pivoted on the casing and connected to the shutter and arranged to be operated by the cam to move the shutter and expose the register through the window.

3. In a taximeter, the combination of a casing provided with a window, a totalizing register located to be viewed through said window, a shutter slidably mounted on the casing and arranged to cover the window in its normal position, a key controlled barrel lock extending through the casing, a cam on the barrel, an angle lever pivoted on the casing and having an arm projecting into the path of the movement of the cam, said lever being connected to the shutter and so arranged that when the lock barrel is rotated, the shutter will be moved to expose the register through the window.

4. In a taximeter, the combination of a casing provided with a window, a totalizing register located to be viewed through said window, a shutter slidably mounted on the casing and arranged to cover the window in its normal position, a key controlled

barrel lock extending through the casing, a cam on the barrel, an angle lever pivoted on the casing and having an arm projecting into the path of movement of the cam, a 5 spring for holding said lever in contact with the cam, said lever being connected to the shutter and so arranged that when the lock barrel is rotated the shutter will move to expose the register through the 10 window.

5. In a taximeter, the combination of a casing provided with a window, a totalizing register located to be viewed through said window, a shutter movably mounted 15 on the casing and arranged to cover the window in its normal position, a key controlled barrel lock extending through the casing, a cam on the barrel, a double arm angle lever pivotally mounted on the casing, one arm thereof connected to the shutter, the other arm being arranged to be engaged by the cam to move the shutter and 20 expose the register through the window,

the respective arms of the angle lever being substantially of the same length. 25

6. In a taximeter, the combination of a casing having a wall or plate, said plate being provided with a window, a totalizing register located to be viewed through said window, a shutter movably mounted in the 30 casing and arranged to cover the window in its normal position, a key controlled barrel lock extending through said wall or plate, and operating connections between said lock barrel and shutter, said connections being 35 mounted upon the inner face of said wall or plate and arranged when the lock barrel is rotated to move the shutter to expose the register through the window.

In testimony whereof, I have hereunto 40 set my hand.

PAUL RICHERT.
